[57] CLAIM

The ornamental design for a cup shaped sole, as shown and described.

DESCRIPTION

FIG. 1 is a side elevational view of one side of a cup shaped sole showing our new design;

FIG. 2 is a side elevational view of the other side of the cup shaped sole shown in FIG. 1;

FIG. 3 is a front elevational view of the cup shaped sole shown in FIG. 1;

FIG. 4 is a rear elevational view of the cupped shaped sole shown in FIG. 1;

FIG. 5 is a bottom plan view of the cup shaped sole shown in FIG. 1;

FIG. 6 is a cross sectional view of the heel area of the sole as shown in section 6—6 of FIG. 5;

FIG. 7 is a cross sectional view of the arch area of the sole as shown in section 7—7 of FIG. 5;

FIG. 8 is a cross sectional view of the tread elements in the ball area of the sole as shown in 8—8 of FIG. 5;

FIG. 9 is a cross sectional view of the boomerang as shown in section 9—9 in FIG. 5;

FIG. 10 is a cross-sectional view including the window element of the cup shaped sole as shown in section 10—10 of FIG. 1;

FIG. 11 is a cross sectional view of the cup shaped sole as shown in section 11—11 of FIG. 1;

FIG. 12 is a cross sectional view of the cup shaped sole as shown in section 12—12 of FIG. 2;

FIG. 13 is a side elevational view of one side of a cup shaped sole according to a second embodiment of our new design;

FIG. 14 is a side elevational view of the other side of the cup shaped sole shown in FIG. 13;

FIG. 15 is a bottom plan view of the cup shaped sole shown in FIG. 13;

FIG. 16 is a cross sectional view of the heel area of the sole as shown in section 16—16 of FIG. 15;

FIG. 17 is a cross sectional view of the arch area of the sole as shown in section 17—17 of FIG. 15;

FIG. 18 is a cross sectional view of tread elements in the ball area of the sole as shown in section 18—18 of FIG. 15;

FIG. 19 is a cross sectional view of the boomerang as shown in section 19—19 of FIG. 15;

The broken line showing of a shoe upper and the internal top and side surfaces of the sole cross sections are for illustrative purposes and form no part of the claimed design.
